UNITED STATES PATENT OFFICE.

ELIJAH MCCOY, OF DETROIT, MICHIGAN.

DESIGN FOR A BICYCLE HANDLE-BAR.

SPECIFICATION forming part of Design No. 34,072, dated February 12, 1901.

Application filed January 9, 1901. Serial No. 42,701. Term of patent 3½ years.

To all whom it may concern:

Be it known that I, ELIJAH MCCOY, a citizen of the United States of America, residing at Detroit, in the county of Wayne and State 5 of Michigan, have invented a certain new and original Design for Bicycle Handle-Bars, of which the following is a specification, reference being had therein to the accompanying drawings, forming part thereof, in which—
10 Figure 1 is a perspective view of a handle-bar, showing my design. Fig. 2 is a plan view thereof.

As shown in the drawings, the leading or material feature of my design consists of the 15 peculiar outline and configuration of the han-

dle-bar formed by the curved side bars A and the grip-bar B, joining the ends thereof, the characteristic feature being the transverse grip-bar B.

Having thus described my invention, what 20 I claim as new, and desire to secure by Letters Patent, is—

The design for a bicycle handle-bar, substantially as herein shown and described.

In testimony whereof I affix my signature 25 in presence of two witnesses.

ELIJAH MCCOY.

Witnesses:

OTTO F. BARTHEL,
LEWIS E. FLANDERS.
